G. C. LEE,
CULINARY LIFTER,
APPLICATION FILED NOV. 7, 1916.

1,238,531.

Patented Aug. 28, 1917.

UNITED STATES PATENT OFFICE.

GEORGE C. LEE, OF BELLEVILLE, NEW JERSEY.

CULINARY LIFTER.

1,238,531.

Specification of Letters Patent. Patented Aug. 28, 1917.

Application filed November 7, 1916. Serial No. 129,973.

To all whom it may concern:

Be it known that I, GEORGE C. LEE, a citizen of the United States, residing at Belleville, in the county of Essex and State of New Jersey, have invented certain new and useful Improvements in Culinary Lifters; and I do hereby declare the following to be a full, clear, and exact description of the invention, such as will enable others skilled in the art to which it appertains to make and use the same.

This invention relates to improvements in culinary lifters.

The object of this invention is to provide a lifter especially adapted for removing hot plates, pans, cups or the like, thus eliminating the use of tea cloths, dish rags, and obviating injury to persons handling the same.

A further object of this invention is to provide a lifter especially adapted to lifting pots, pans, jars, cuspidors, and plates of all shapes, and is adapted for the lifting of covers or the like from pots and pans and one that can be easily and quickly manipulated.

A still further object of this invention is to provide a lifter formed of a single piece of wire which is so constructed as to provide a pair of spring clamp arms which will effectively grip an article therebetween so that the same may be readily removed from or placed upon a stove or the like.

A still further object of this invention is to provide a lifter of this character which will be simple, practical, and comparatively inexpensive in construction and one that can be manufactured and sold at a comparatively small cost.

With these and other objects in view the invention consists in the novel combination and arrangement of parts hereinafter more fully described and set forth in the claim hereto appended.

In the drawings:

Figure 1 is a top plan view of my lifter as made in accordance with this invention illustrating the manner in which the article is held therebetween.

Fig. 2 is a similar view illustrating the manner in which the larger pan, plate or the like is held therebetween.

Fig. 3 is a side elevation of the same.

Fig. 4 is a top plan view illustrating the manner in which a cover is removed from a pot, pan or the like.

Like numerals of reference designate cor-

responding parts in all the figures of the drawing.

Referring more particularly to the drawing, the numeral 1 designates the lifter in its entirety which comprises in its construction a single piece of wire or other resilient material which is looped at its medial portion as at 2 to provide a pair of divergent resilient arms 3. The arms 3 are provided intermediate their ends with diametrically opposed laterally projecting bends 4 and 5. The laterally projecting bend 5 being of a diameter greater than the bend 4 and adapted to receive therein knobs of covers or pans, or the like of various sizes so that the same may be readily removed from pots, pans, or the like. The divergent ends of the arms 3 are looped as at 6 and are extended forwardly as at 7 and bent back upon themselves as at 8 to form a pair of clamping members. The extreme ends of the upper clamping members are extended through the loop 6 and bent back upon itself as at 9 to firmly secure the same therein and arrange the portions 7 and 8 in superposed relation to provide clamping members which will firmly grip and clamp cups, jars or the like.

The extended portions 7 of the arms are bent back upon themselves as at 10 as clearly shown in Fig. 3 of the drawings.

The members 7 and 8 of the arms 3 are curved longitudinally to present concave inner faces 12 which permits the arms to readily grasp articles of various sizes therebetween. The portions 3 of the diverging arms are grasped by the hands of the operator and the clamping members 7 and 8 are arranged around an article such as pans, plates, or the like and pressure is applied to the members 3 forcing the same inwardly to firmly grasp the article between the opposing concave faces of the clamping members 7 and 8 and the articles may be readily lifted.

When it is desired to remove the top lid or cover, the laterally offset portions 4 and 5 are slipped around the knob designated A of the cover B and the same is removed from the receptacle, as clearly shown in Fig. 4 of the drawing.

What is claimed is:

A pan lifter constructed of a single length of wire bent at its medial portion to provide a pair of divergent resilient arms, said arms provided intermediate their ends with diametrically opposed laterally projecting

bends which are adapted to receive the knobs of covers of pans to facilitate raising of the covers from pots, pans, or the like, the terminals of the arms looped back upon themselves in a vertical plane and extended forwardly, and bent back upon themselves and having their terminals arranged in the looped portion to provide a pair of upper and lower bars which constitute plate or pan 10 engaging members, said vertical loop of

each arm facilitating the fastening of the ends of the pan engaging members therein for providing a rigid connection when assembled.

In testimony whereof I affix my signature 15 in presence of two witnesses.

GEORGE C. LEE.

Witnesses:

GEORGE FRANK,
ANDREW HAUCK.
